UNITED STATES PATENT OFFICE.

ROLANDIS A. BLAIR, OF FORT WAYNE, INDIANA, ASSIGNOR TO THE P & M COMPANY, OF CHICAGO, ILLINOIS, A CORPORATION OF ILLINOIS.

RAIL ANCHOR.

Application filed January 15, 1926. Serial No. 81,406.

My invention relates to rail anchors and has for its principal object the provision of a one-piece anchor device of novel and improved construction which may be made of 5 relatively light stock without sacrificing the strength required in devices of this character to resist the creeping movement of railroad rails.

A more specific object is to provide an improved one-piece resilient anchor which is so formed as to be tensioned during its application to a rail to effect a strong spring grip on opposite edges of the rail base and which will be further tensioned when the device is 15 pressed against a cross tie by the longitudinal creeping movement of the rail.

The invention has for a further object, the provision of a rail anchor device having the improved arrangement and construction of 20 parts hereinafter described and claimed for carrying out the above stated objects, and such other objects as will appear from the following description of the embodiment shown in the drawing.

25 In the drawing:

Fig. 1 is a plan view of a railroad rail, showing a rail anchor device constructed in accordance with my invention applied thereto.

30 Fig. 2 is a side elevation of the anchor device shown in Fig. 1 showing the anchor in its applied position on the base flange of a rail, and showing in dotted lines a position assumed by the anchor during its application to the rail, and

35 Fig. 3 is a view in perspective of the anchor device shown in Figs. 1 and 2.

The embodiment of my invention shown in the drawing, consists of a yoke 10 which 40 extends across the rail beneath the base 11 thereof, and engages the opposite edges of said base. The yoke is made, preferably, from a single piece of resilient metal bent at the middle, as indicated by the reference 45 numeral 12, to provide two arms 13 and 14. The upper edges of the arms, intermediate their ends, are recessed to provide shoulders 15, 15^a at one side of the rail and shoulders 16, 16^a at the other side. The shoulders 15, 50 15^a are notched to provide vertical edges 17, 17^a adapted to bear against the vertical edge 18 of one base flange of the rail, and to provide small jaws 19, 19^a which fit over the upper corners of the said base flange. The 55 upper portions of the jaws 19, 19^a are in-

clined upwardly, so as to provide cam surfaces 19^b. The bend 12 is formed preferably with a radius of such length that the jaws 19, 19^a are normally spaced apart and so that the arms may converge toward the opposite edge of the rail base. The angle of convergence of said arms is preferably such that they normally engage each other adjacent the shoulders 16, 16^a, the latter being spaced a short distance away from the edge 20 of 65 the rail base. The end portions 21, 22, of the arms are bent in opposite directions so as to be substantially parallel to the adjacent edge of the rail base when the anchor is applied to the rail. The extremities of the edge portions 21, 22 are bent inwardly and are recessed to provide jaws 23, 23^a and 24, 24^a adapted to grip, with firm wedging engagement, the upper and lower surfaces of the 70 rail base. The lower jaws are made somewhat longer than the upper jaws, so as to provide a relatively large surface for engagement with the cross tie or other stationary part of the road-bed. The distance from the vertical edge 17, 17^a to a horizontal line drawn through the vertical surfaces 25, as represented by S in Fig. 3, is normally less than the width of the rail base, whereby the end portions 21, 22, are flexed inwardly 75 toward the adjacent edge of the rail base when the jaws 19, 19^a are forced over the opposite edge of the rail base.

In applying the anchor to a rail, the jaws 23, 24, are hooked over one edge of the rail base, substantially as shown in dotted lines 80 in Fig. 2. The end 12 of the anchor is then forced upwardly to force the cam surfaces 19^b and the jaws 19, 19^a over the rail base. The pressure of the cam surfaces 19^b against the edge of the rail moves the arms 13, 14, 95 bodily transversely of the rail, and flexes the angularly disposed ends 21, 22 from the dotted line position of Fig. 1 to the full line position. As soon as the jaws 19, 19^a clear the upper edge 18 of the rail base, the resiliency of the metal from which the device is 100 formed causes the said jaws 19, 19^a to snap over the upper edge of the rail base. After the jaws 19, 19^a snap into position, the jaws at the opposite edge of the rail may be driven 105 into wedging engagement with the rail base. The resiliency of the metal exerts a strong spring grip upon the rail, which in itself will ordinarily be sufficient to resist the creeping movement of the rail. Any creep- 110

ing movement of the rail, however, will tend to move the jaw 19^a toward the cross tie 26 and thereby subject the yoke to increased tension.

5. While I have described my invention in connection with one specific embodiment, it will be obvious that modifications might be made without departure from the spirit of my invention. I therefore wish it understood that I contemplate all such changes in construction as come within the scope of the appended claims.

I claim:

1. A rail anchor comprising a yoke provided with spaced arms connected at one end, jaws at the free ends of said arms adapted to fit over one edge of the rail base at points remote from said arms, and jaws at the connected ends of said arms adapted to fit over 20 the other edge of the rail base; the jaws at one side of the rail being so disposed with relation to the jaws of the other side, that it is necessary to tension the yoke in applying it to a rail.

25. 2. A rail anchor comprising a yoke formed from a single metal strip to provide spaced arms connected at one end, jaws at the free ends of said arms, adapted to fit over one edge of the rail base at points 30 remote from said arms, and jaws at the connected end of said arms adapted to fit over the other edge of the rail base; the jaws at one side of the rail being so disposed with relation to the jaws at the other side that it is necessary to tension the yoke in applying it to a rail.

35. 3. A rail anchor comprising a yoke formed from a single strip of spring metal bent to provide spaced arms connected at one end 40 and converging toward the other, jaws at the free ends of said arms adapted to fit over one edge of the rail base at points remote from said arms, and jaws at the connected ends of said arms to fit over the other edge of the 45 rail base; the jaws at one side of the rail being so disposed with relation to the jaws of the other side that it is necessary to tension the yoke in applying it to a rail.

50. 4. A rail anchor comprising a yoke provided with spaced arms connected at one side of a rail and converging toward the other side, spaced jaws at the connected ends of said arms for engagement with one base flange of the rail, the free ends of said arms being bent in opposite directions at the other side of the rail and formed with jaws for engaging the top and bottom surfaces of the rail base.

55. 5. A rail anchor comprising a yoke provided with spaced arms connected at one side of a rail and converging toward the other side, spaced jaws at the connected ends of said arms for engagement with one base flange of the rail, the free ends of said arms

being bent in opposite directions at the other side of the rail to provide angularly disposed end portions and formed with jaws for engaging the top and bottom surfaces of the rail base.

6. A rail anchor comprising a yoke provided with spaced arms connected at one side of a rail and converging toward the other side, spaced jaws at the connected ends of said arms for engagement with one base flange of the rail, the free ends of said arms being bent in opposite directions at the other side of the rail to provide angularly disposed end portions and formed with jaws for engaging the top and bottom surfaces of the rail base; the arrangement of the 80 jaws at one side of the rail with relation to the other side being such that the angularly disposed end portions are flexed inwardly toward the adjacent edge of said base when applying the yoke to a rail.

7. A rail anchor comprising a yoke formed from a single piece of metal bent to provide converging arms which normally engage each other at one side of the rail, spaced jaws at the connected ends of said arms for engagement with one base flange of the rail, the other ends of said arms being bent in opposite directions to a position substantially parallel with the adjacent edge of the rail base and formed with jaws adapted to have a wedging engagement with the upper and lower surfaces of said base.

8. A rail anchor comprising a yoke provided with spaced arms connected at one side of a rail and converging toward the other side, angularly disposed end portions at the free ends of said arms, which normally extend parallel to the adjacent edge of the rail base and provided with jaws adapted to engage the said rail base at points remote from said arms, the said arms adjacent their connected ends being provided with jaws adapted to snap over the upper edge of said base flange.

9. A rail anchor comprising a yoke member formed with two arms connected at one end and adapted to bear against each other at the other end, the free ends of said arms being bent in opposite directions and formed with jaw portions engaging the upper and lower surfaces of the rail base and the connected ends of said arms being provided with jaws formed with inclined cam surfaces adapted to ride over the opposite edge of the rail base; the jaws at one side of the rail being so disposed with relation to the jaws at the other side that the angularly disposed end portions of said arms are flexed toward the adjacent edge of the rail base when the connected ends of said arms are forced upwardly to move the jaws at this end into engagement with the rail base.
